ORCHARD HEATER

Charles F. Yawman, Jr., Ontario, Calif.

Application August 31, 1950, Serial No. 182,509

7 Claims. (Cl. 126—59.5)

1

My invention relates to a burner for liquid fuel and is intended particularly for use in orchard heaters, although capable of use for various other purposes.

One drawback of many orchard heaters which use liquid fuel consists in the fact that their fuel supply must be replenished, preferably in the daytime, but sometimes at night, as when there is a shortage of labor or of fuel. A factor that makes this work dangerous as well as disagreeable is the fact that the clothing of workers becomes soaked with oil, which is not only cold to the wearer but all too frequently becomes ignited and gives rise to dangerous burns and sometimes to fatal burns. It has been proposed to install a system of burners that are connected by pipe lines to a common source of supply, but the cost of installation and upkeep of such a system is so high as to be almost prohibitive, the pipes interfere with various necessary horticultural operations, and in general such schemes have not proved satisfactory. Even with such systems, their operation is improved by use of a burner as herein disclosed, since their operation is made more practical and effective due to the automatic regulation within the self-contained burner units.

It is an object of my invention to provide orchard heaters that can be placed sufficiently close together to protect an orchard against any ordinary "freeze" and, in fact, to protect most orchards even against a "great freeze" such as may be expected only once in about seven to ten years, but which can hold sufficient fuel to burn through even the entire night if necessary, without exhaustion of fuel.

Another object is to provide orchard heaters that are simple and inexpensive to manufacture, requiring little attention and little or no upkeep during their useful life.

Another object is to provide a liquid fuel burner that shall be self-regulating in that the supply of fuel is reduced or cut off if too large a supply of gas is being formed.

Another object is to provide a liquid fuel burner that shall be efficient in consumption of fuel, leaving very little, if any, non-consumable residue and being smokeless, or substantially so, in its operation.

Referring to the annexed drawings, which are made a part of this application, and in which similar reference characters indicate similar parts:

Fig. 1 is an elevation of the device of my invention, partly in section,

2

Fig. 2 is a section on line 2—2 of Fig. 1, Figure 3, a section on line 3—3 of Fig. 1, and Fig. 4, a section of a float valve shown in Fig. 1.

5 In the drawings, reference character 10 indicates a tank, supported on legs 11 and provided, at a convenient height for refilling, with a lid 12 hinged to the tank at 13. A conduit 14 leads down from the tank to the outer end of a tubular retort 15. Preferably the conduit 14 consists of two pipe sections 17 and 18 and section 17 is provided with a manually operable valve 16, e. g., a needle valve or the like, for shutting off the supply of fuel. In a descending portion of the pipe there is provided a float valve (Fig. 4) between the two pipe sections 17 and 18, said valve comprising a casing 19 providing a chamber for a ball 20 which is preferably of durable material, such as metal of suitable size and weight, and a seat at 21 in the top of the chamber. The pressure of the gas formed in the retort will lift the ball and should keep it near the top of the valve chamber, so that the flow of liquid fuel to the retort is automatically regulated by the floating action of the ball riding on the liquid fuel.

10 The retort 15 is formed as a substantially annular tube extending about the interior of a frustoconical shroud 22 near the upper end of said shroud and has adjacent its outlet end an arm 23 extending radially inward approximately to the center of the shroud, said arm being connected to the spiral body of the retort by a downwardly extending portion 23'. The shroud is flared upwardly somewhat from its smaller lower end to its larger upper end to provide space for expansion of the contained hot air and gas. It is supported on a pan 24 by legs 25 which space it from the pan to permit entrance of air at the lower end of the shroud.

15 The retort is supplied at the inner end of arm 23 with a plug 26 for use as a clean-out device at the end of the season or at other times as needed. The pipe portions 23 and 23' serve as a trap for non-consumable residues or other foreign material.

20 A baffle 27 which is spiral as seen in plan is supported from the retort by means of brackets 28, 28 that engage over parts of the retort and have depending legs secured to the baffle. The baffle, which may be made of sheet metal or the like, is preferably bent so as to encircle the axis of the shroud in spaced relation to the trap 23', 23 and extending upward from the level of the same. At its outer end the baffle extends 25 nearly to the outlet port of a nozzle 29 in such

relation to the same as to split the jet of flaming gas issuing from said port, causing a whirling current of flame to circulate about the inner periphery of the shroud adjacent the retort, and another like current to circulate inside the baffle and about the axis of the baffle. The outer vortex is mainly effective in heating the retort to gasify the fuel therein, whereas the inner vortex acts to insure complete combustion of gas and any residual liquid fuel issuing from port 29 by mixing flame back into flame and maintaining a high temperature for complete gasification at this point. Air enters the lower end of the heater at the space between pan 24 and the lower margin of the shroud, and hot air passes upward out of the shroud in obvious manner. The depending parts 23 and 23' provide space for collection of any residues, and keep them out of the way of the gas passing to the outlet of nozzle 28, so as to prevent interference with the feed to said port.

It will be obvious to those skilled in the art that many changes may be made in the device herein disclosed, all without departing from the spirit of the invention; and, therefore, I do not limit myself to what is shown in the drawings and described in the specification, but only as indicated in the appended claims.

Having thus described my invention, what I claim is:

1. An orchard heater comprising a shroud having a circular wall about an upright axis, a tubular retort within said wall and parallel thereto, means for supplying liquid fuel to said retort, an outlet nozzle connected with said retort, and a baffle having its leading edge positioned to split a jet issuing from said nozzle, said baffle being substantially concentric with said shroud to provide therewith concentric whirling currents of flame within the shroud.

2. A device as in claim 1, including a downward terminal extension on the retort for collection of non-consumable residues, a drainage port on said extension, and a plug for the port.

3. An orchard heater comprising a liquid fuel burner having an outer shroud formed as an inverted frustum of a cone mounted on a vertical axis, an annular tubular retort in said shroud and substantially concentric therewith, means

for supplying liquid fuel to said retort, an outlet nozzle for said retort, and a baffle substantially concentric with said shroud, said baffle having a leading edge positioned to split the jet of gasified fuel issuing from said nozzle into vortical inner and outer currents.

4. An orchard heater comprising an upright shroud having a circular wall, a conduit for liquid fuel, said conduit having a body portion spaced inwardly from said wall and approximately concentric therewith and forming a retort for gasifying the fuel, a sheet metal baffle below the retort, said baffle having a portion approximately coaxial with the retort, an outlet nozzle for said retort, said nozzle being so positioned with reference to the leading edge of the baffle as to split the jet of gasified fuel issuing from the nozzle into inner and outer whirling currents, substantially as set forth.

5. A device as in claim 4, including a pan fixed to the shroud in spaced relation to the lower end of the same, so as to admit air to the burner.

6. A device as in claim 4, wherein the conduit includes a downwardly extending terminal portion, an end portion extending from said depending portion to the axis of the shroud for collecting non-consumable residues and a drainage plug in said last-named conduit portion.

7. A device as in claim 6, and a pan spaced from the shroud and fixed thereto for receiving the unconsumed drainage from the retort.
